UNITED STATES PATENT OFFICE.

CHARLES G. CURTIS, OF NEW YORK, N. Y., ASSIGNOR TO THE CURTIS COMPANY, OF SAME PLACE.

ELASTIC-FLUID TURBINE.

SPECIFICATION forming part of Letters Patent No. 595,435, dated December 14, 1897.

Application filed August 4, 1896. Serial No. 601,603. (No model.)

To all whom it may concern:

Be it known that I, CHARLES G. CURTIS, a citizen of the United States, residing at New York city, in the county and State of New York, have invented a certain new and useful Improvement in Elastic-Fluid Turbines, of which the following is a specification.

The object I have in view is to produce an elastic-fluid turbine operating under conditions of high efficiency in which variations in speed may be effected without great variations in the efficiency of operation. This I accomplish by constructing and arranging the fluid-passages of the turbine and their connections in such a way that the elastic fluid may be caused to traverse the movable vanes a greater or less number of times in succession. With a definite speed of rotation of the movable vanes and a definite total velocity developed in the elastic fluid the passage of the elastic fluid through the movable vanes a certain number of times is required to absorb substantially all the velocity developed and convert it into mechanical motion, but if the speed of the vanes be increased or decreased the number of passages required to extract substantially all the velocity developed will be smaller or greater. Therefore by varying the number of times that the elastic fluid is caused to act upon the movable vanes the speed of revolution of the turbine may be varied without materially altering the efficiency of operation. The turbine may have a single set of movable vanes, through which the elastic fluid will be passed a variable number of times in succession, or the same result may be accomplished in a turbine having two or more sets of movable vanes; but I prefer to construct the turbine with a number of sets of movable vanes, each inclosed in a separate fluid-tight shell, the number of separate sets of vanes corresponding with the maximum number of fluid-passages required, and by means of these several sets of vanes and suitable nozzles and connecting-passages I propose to convert the pressure of the elastic fluid into velocity and transform the velocity into mechanical motion by stages, the number of expansion stages being varied while maintaining practically the same total expansion.

In the accompanying drawings, Figure 1 is a section through the rotating vanes and the successive nozzles of one form of the apparatus; and Fig. 2 is a similar view, largely 55 in outline, of a modification of the apparatus.

Referring particularly to Fig. 1, A, B, C, and D are rotating wheels carrying vanes, forming vane-passages which are inclosed in separate fluid-tight shells E, F, G, and H, the 60 general plan of the elastic-fluid turbine being such as is described in Patent No. 566,969, issued to me September 1, 1896. These four wheels are mounted on a common shaft and form elements of one turbine. I, J, K, and L 65 are a series of expansion-nozzles delivering the elastic fluid to the several wheels in succession. M is the pipe from the steam-boiler or other source of elastic fluid under pressure, and N, O, P, and Q are the exhaust-openings 70 for the several wheels, placed opposite the discharging ends of the respective nozzles. The exhaust-passages N O P are intermediate stationary passages or conduits which lead the elastic fluid from the wheels A, B, and C, 75 respectively, to the nozzles J, K, and L. The passages N, O, and P are connected by pipes R S T, provided with suitable valves, with the exhaust, whether condensing or atmospheric. Each of the nozzles I, J, K, and L 80 has an adjustable piece U, forming one side of the expansion-nozzle and serving to change the angle of divergence of the nozzle and the ratio of conversion of pressure into velocity. The adjusting devices for moving the pieces 85 U may be connected together and operated simultaneously, or they may be operated independently, as shown. Each of the expansion-nozzles is also provided with an adjustable tongue V, forming one of the diverging 90 sides of the nozzle, which by its adjustment is adapted to vary the cross-sectional area of the nozzle without varying the ratio of expansion, so as to make the nozzle larger or smaller to adapt it to carry the volume of 95 the elastic fluid which it may be required to carry under the different conditions of operation, which volume will be greater or less according to whether the total expansion is produced in a lesser or greater number of 100 nozzles. To secure the lowest rate of speed, the valves in the exhaust-pipes R, S, and T

are closed and the elastic fluid is caused to pass through the four wheels A, B, C, and D. The pieces U of the four nozzles are adjusted so as to produce at the discharging end of each nozzle practically the same velocity, the tongues V being also adjusted to provide the proper cross-sectional area, thus converting the pressure into velocity and extracting it in four stages. If a higher rate of speed is desired, the exhaust-pipe T is opened, thus cutting out the wheel D and causing the fluid to act upon three wheels only. The pieces U of the three nozzles I, J, and K are now adjusted to convert the pressure into velocity in three stages, and the tongues V of these nozzles being drawn back sufficiently to give the increased cross-sectional areas over that required when the four nozzles are employed. Under these circumstances the velocity produced by each nozzle will be greater than in the case of four nozzles and the speed of the wheels will be greater. Likewise, if the exhaust-pipe S is opened only two wheels will be in action, and the nozzles I and J will be adjusted to give the proper conversion of pressure into velocity and the proper cross-sectional area, securing in each instance a higher velocity than with three nozzles. Likewise, if the exhaust-pipe R is opened only the wheel A will be acted on by the fluid and the nozzle I will be adjusted so as to convert practically all the available pressure into velocity and to give the proper cross-section for the fluid-jet. In Fig. 2 the same four wheels are illustrated; but four separate sets of passages through these wheels are employed, each set of passages being proportioned to give the proper conditions of operation. The series of nozzles and connecting-passages to the right of the figure connect the four wheels in succession, giving the proper conversion of pressure into velocity at each wheel. The next set of passages to the left connects the three wheels in succession, giving a greater production of velocity for each wheel. The next set of passages to the left connects two wheels in succession, giving a still greater conversion of pressure into velocity for each wheel, and the last nozzle to the left acts only upon one wheel and is proportioned to convert substantially all the pressure into velocity. Each of the sets of nozzles is connected with the steam-boiler or other source of elastic fluid under pressure by a conduit or pipe which is provided with a suitable throttle-valve, and the intermediate passages connecting the wheels also have valves to prevent the

fluid in the shells from escaping through other than intended passages.

60

What I claim is—

1. An elastic-fluid turbine provided with controllable passages whereby the elastic fluid may be caused to act upon movable vanes a greater or less number of times in succession 65 so as to secure different rates of speed economically, substantially as set forth.

2. An elastic-fluid turbine wherein the pressure of the elastic fluid is converted by expansion into velocity, and the velocity converted into mechanical motion, by stages, such turbine being provided with means for varying the number of expansion stages while maintaining practically the same total expansion, so as to obtain different speeds economically, substantially as set forth. 75

3. In an elastic-fluid turbine, the combination with two or more sets of rotating vanes, of passages whereby the elastic fluid may be passed through different numbers of movable 80 vanes in succession and different rates of speed may be secured, substantially as set forth.

4. In an elastic-fluid turbine, the combination with a number of rotating wheels, of expansion nozzles or passages delivering the fluid to the wheels in succession, and connections whereby the fluid may be delivered to different numbers of such wheels, substantially as set forth. 85

5. In an elastic-fluid turbine, the combination of a number of rotating wheels and a number of expansion-nozzles delivering the elastic fluid to the several wheels in series or succession, such nozzles being adjustable to 95 vary their cross-sectional area and also to vary the ratio of conversion of pressure into velocity, and exhaust connections from each wheel, whereby the number of wheels through which the fluid is passed may be varied and 100 the speed changed, substantially as set forth.

6. In an elastic-fluid turbine, the combination of two or more wheels A, B, &c., two or more expansion-nozzles I, J, &c., having adjustable pieces U for varying the ratio of expansion and tongues V for varying the cross-sectional area of the nozzles, one or more connecting-passages N, &c., and one or more exhaust connections R, &c., substantially as set forth. 105

This specification signed and witnessed this 30th day of July, 1896.

CHARLES G. CURTIS.
